UNITED STATES PATENT OFFICE.

JOSEPH F. MENNINGEN, OF WEST ALLIS, WISCONSIN, ASSIGNOR, BY MESNE ASSIGNMENTS, TO ALLIS-CHALMERS MANUFACTURING COMPANY, A CORPORATION OF DELAWARE.

CONNECTOR.

1,104,436.

Specification of Letters Patent. Patented July 21, 1914.

Application filed January 30, 1909. Serial No. 475,287.

To all whom it may concern:

Be it known that I, JOSEPH F. MENNINGEN, a citizen of the United States, residing at West Allis, in the county of Milwaukee and State of Wisconsin, have invented certain new and useful Improvements in Connectors, of which the following is a full, clear, and exact specification.

My invention relates to separable connectors or couplers for electric circuits.

It is advantageous to be able to make quick and reliable connections between conductors in an electric circuit and at the same time make secure connections of high efficiency.

The object of my invention is to provide an inexpensive coupler by which connections may be made or broken quickly and without the assistance of tools, in which the parts are duplicate and interchangeable, and in which there is sufficient contact area to cause the resistance of the joint to be inappreciable.

In carrying out my invention I provide a connector for electric circuits comprising two coöperating parts, each part including male and female knife blade contacts complementary to the female and male contacts on the other part and so located that when the two parts are together the two female contacts overlap.

More specifically considered my invention consists in an electric connector, comprising two duplicate parts, each part comprising a shell for the reception of a conductor, a female knife blade contact, and a male knife blade contact complementary to the female contact and located between the latter and the shell.

In the accompanying drawing Figure 1 is a view of a connector embodying my invention and showing the manner in which the connection is made; and Fig. 2 is a perspective view of one of the duplicate parts of the connector.

My connector comprises two duplicate coöperating parts, 16 and 17, which I prefer to make, as shown, of some good resilient sheet metal or conducting material, which is punched out, by means of dies, to the desired shape and dimensions, and then finished up to take the form shown in Fig. 2. Each part includes a male contact 13 and female contact 14, and a shell 12 for the reception of a connector 10. These two contacts are respectively complementary to the female and

male contacts on the other part, and so located that when the two parts are together the two female contacts 14 overlap, i. e. the male contact is between the female contact and the shell. The female contacts have two fingers, 18 and 19 respectively, and an integral portion connecting these fingers at the back thereof, thus forming a pocket closed on three sides, and the extremities of the fingers so shaped as to form inwardly projecting tips, 20 and 21, which lap over the back of the male contacts to hold or lock the male contact of the other part when the connection is complete. By means of this arrangement the coöperating parts are tightly clamped together preventing separation of the parts when subjected to anything short of a forceful transverse strain. The duplicate interchangeable parts are preferably, but not necessarily, in line axially of the connector. In these two coöperating parts, the male members might be called the wrists and the female the fingers of the connector. When the connection is complete the wrists of the two interchangeable parts are each gripped by the fingers of the other part so that there can be no relative longitudinal movement between the two parts.

It might be stated that relative longitudinal movement of the parts is prevented by means of having the effectual engaging lengths of the male and female parts equal, the remaining portions of the male parts being of such increased dimensions to render further reception by the female parts impossible.

Many modifications may be made in the arrangement here specifically shown and described, and I aim in my claims to cover all modifications which do not involve a departure from the spirit and scope of my invention.

What I claim as new is:—

1. A connector for electric circuits, comprising two interchangeable parts, each of said parts including male and female contacts in line with each other axially of the connector, the female contacts being formed of a single piece of material and being bent to close three sides for engagement with the male contact members.

2. An electric connector, comprising two duplicate parts, each part including a shell for the reception of a conductor, a female contact, and a male knife blade contact lo-

cated between the female contact and the shell and complementary to the female contact on the other part, the female contacts being formed of a single piece of material 5 and being bent to close three sides for engagement with the complementary male contacts.

3. A connector for electric circuits, comprising two duplicate parts, each of said 10 parts consisting of sheet metal shaped to form a shell for the reception of a conductor and complementary male and female contacts in line with each other, the female contacts being bent to close three sides for engagement with male contact members.

4. An article of manufacture, comprising a shell for the reception of a conductor, and male and female contacts, the male contact being between the female contact and the 20 shell, and the female contact being bent to close three sides thereof for engagement with a coöperating male contact.

5. A connector for electric circuits, comprising two coöperating parts, each part including a contact wrist and contact fingers respectively complementary to the contact fingers and wrist on the other part and so located that when the two parts are together there can be no relative longitudinal move- 25

ment between them, the contact fingers being integrally formed to close three sides to be engaged by complementary contact wrists.

6. A connector for electric circuits, comprising two coöperating parts, each part including a conductor attaching portion and male and female contacts respectively complementary to female and male contacts, on the other part, and said male contact being provided with a shouldered portion adjacent 35 said conductor attaching portion, said shouldered portion and said female contact acting to lock a complementary female contact in engagement with said male contact.

7. An article of manufacture, comprising a single piece of sheet metal having a portion for attachment to a conductor, and male and female contact portions, the male contact portion being between the female contact portion and the conductor attaching portion and being attached directly to both 40 of said latter portions.

In testimony whereof I affix my signature, in the presence of two witnesses.

JOSEPH F. MENNINGEN.
